Primary Examiner — Vy N Koenig*Assistant Examiner* — Qiawen W Wiechert(74) *Attorney, Agent, or Firm* — PV IP PC; Wei Te Chung(57) **CLAIM**

The ornamental design for a liquor cabinet as shown and described.

DESCRIPTION

FIG. 1 is a front view of a liquor cabinet showing my new design;

FIG. 2 is a back view thereof;

FIG. 3 is a left view thereof;

FIG. 4 is a right view thereof;

FIG. 5 is a top view thereof;

FIG. 6 is a bottom view thereof;

FIG. 7 is a perspective view thereof; and,

FIG. 8 is an enlarged view of the area labeled “8” in FIG. 7. The cabinet door is made of translucent material, and the surface of the cabinet door has a concave wavy texture. The evenly dashed broken lines in the drawings are for the purpose of illustrating portions of the liquor cabinet that form no part of the claimed design.

The dot-dash broken lines illustrate the borders of the enlarged views and form no part of the claimed design.
